GEORGE W. KELLOGG, OF ROCHESTER, NEW YORK, ASSIGNOR TO KELLOGG MANUFACTURING COMPANY, OF ROCHESTER, NEW YORK, A CORPORATION OF NEW YORK.

FLUID-PUMP.

1,187,531.

Specification of Letters Patent. Patented June 20, 1916.

Application filed September 21, 1914. Serial No. 862,843.

REISSUED

To all whom it may concern:

Be it known that I, GEORGE W. KELLOGG, of Rochester, in the county of Monroe and State of New York, have invented certain new and useful Improvements in Fluid-Pumps; and I do hereby declare the following to be a full, clear, and exact description of the same, reference being had to the accompanying drawings, forming a part of this specification, and to the reference-numerals marked thereon.

The present invention relates to fluid pumps, with more particular reference to the type of pump that is employed for obtaining air and other light fluids under pressure, and it has for its object to provide a novel construction and arrangement of the several parts, affording a machine that is characterized by great compactness and lightness of weight, while at the same time resulting in extreme efficiency in operation.

A further object of the invention consists in so combining the several parts as to afford a balanced structure operating under a minimum amount of friction, and which can be successfully applied to small units.

Still another purpose of the invention is found in the provision of lubricating means that prevents the admission of any lubricant into the pressure chamber or into the fluid passing through the pump.

Another object that the invention contemplates is the provision of novel features affecting the connection between the drive shaft and the piston, whereby greater capacity and strength is obtained.

To these and other ends the invention consists in certain improvements and combinations of parts, all as will be hereinafter more fully described, the novel features being pointed out in the claims at the end of the specification.

In the drawings: Figure 1 is a side elevation of a pump constructed in accordance with the invention. Fig. 2 is a longitudinal vertical sectional view. Fig. 3 is a transverse vertical sectional view on the line 3^a—3^a of Fig. 2, and Fig. 4 is a horizontal sectional view on the line 4^a—4^a of Fig. 2.

Similar reference numerals throughout the several views indicate the same parts.

The invention is susceptible of many different applications, and has been designed primarily for the purpose of providing a

small, light, compact structure possessing a high degree of efficiency, such as is employed as an adjunct to automobile construction, to afford a means for carrying a supply of air under pressure at all times without occupying much space or adding substantial weight to the machine.

In the present embodiment, which is a practical illustration of one application of the invention, A designates a base provided with bearings A' within which is journaled the drive shaft B. The latter has fixed thereon a pair of eccentrics C which are arranged in spaced relation to each other, and constitute a part of the connecting means between the drive shaft and the piston which is to be hereinafter described.

Detachably arranged on the base A is a cylinder D, that is comparatively short in order to reduce the weight and size of the machine as much as possible, and the cylinder may be secured on the base in any desirable manner as by means of screws D' which engage alined openings in the cylinder and base. The cylinder is provided with intake and outlet valves D^a controlling the passages leading to and from the cylinder and these are of the usual construction such as employed in this type of machinery.

Arranged for reciprocatory movement within the cylinder D is a piston E that is comparatively short and wide corresponding to the proportion of the cylinder so that while only a short stroke is imparted to the piston, the reduction is more than offset by the increased cross sectional area of the piston and cylinder. The piston E is provided with flexible packing rings E' seated in grooves E^a, and carries a downwardly projecting extension E^b which is connected by a wrist pin E^c with the eccentric straps E^d surrounding the aforesaid eccentrics C. It will be noted that the connecting devices between the piston and drive shaft are disposed in spaced relation to each other on opposite sides of the axial line of the piston thereby balancing the movement of the latter and increasing the power of the machine while at the same time affording an arrangement that permits of successfully guiding the movement of the piston and retaining it at all times in proper relation at right angles to the axis of the cylinder. To this end I form on the extension E^b, at the lower part thereof, a yoke por-

tion E⁶ which straddles the drive shaft B, the arms of the yoke portion being such a distance apart as to closely engage the drive shaft during the travel of the piston. This 5 serves to hold the piston in proper alignment, so that its travel in the cylinder is subjected to the smallest possible amount of frictional resistance.

It is highly desirable in a pump of this 10 character to afford lubrication for the parts without permitting any of the lubricating fluid from entering or mixing with the fluid under pressure, and this I have accomplished in a novel manner by means which 15 I will now describe. F designates the oil chamber in the base A, and at the upper portion of the base is a baffle F' preferably formed integral with the base and operating to cause the lubricating oil to be projected 20 toward the center of the under surface of the piston rather than toward the wall of the cylinder as would be the case if the baffle were not provided. Arranged on the upper side of the baffle F' is an annular ring F² 25 of suitable absorbent material, preferably absorbent wool which catches the lubricant as it is thrown downwardly from the piston and holds it, up to the point of full saturation, the surplus lubricant dropping back 30 into the oil chamber in the base. This action is facilitated by providing the piston on its under surface with deflecting means, which in the present instance consists of recessed portions F³ terminating at a distance from 35 the edge of the piston, affording curved shoulders F⁴. These deflect the oil downwardly before it reaches the edge of the piston, causing it to fall initially onto the absorbent ring F². When the piston travels 40 downwardly it contacts with the ring F², thus slightly lubricating the outer portion of the lower face of the piston and supplying the requisite amount of lubrication to the inner wall of the cylinder as the piston 45 travels upwardly. This prevents an excess of oil from coming into engagement with the walls of the cylinder, so that none of the lubricant will be carried past the piston and injected into the fluid undergoing compression. The oil chamber is filled through an 50 opening controlled by a plug F⁵, and F⁶ designates an air opening for the base, covered by the screen F'.

The invention affords an extremely simple 55 arrangement that can be manufactured at low cost, and presents great advantages in efficiency of operation. The structure is compact and can be readily handled, requiring little space and adding but a small 60 weight to the machine to which it is applied.

I claim as my invention:

1. In a pump, the combination with a base 65 having an oil chamber located therein, of a cylinder arranged on the base, a piston reciprocating within the cylinder, a baffle lo-

cated at the bottom of the cylinder, and an absorbent member disposed above the baffle.

2. In a pump, the combination with a base having an oil chamber located therein, of a cylinder detachably arranged above the 70 base, a piston reciprocating within the cylinder, a baffle located at the bottom of the cylinder, an absorbent member disposed above the baffle in juxtaposition thereto, and deflecting means on the lower face of the 75 piston.

3. In a tire pump, a crank case having an opening in its circumferential wall and an inwardly projecting flange defining said opening and constituting a baffle ring and 80 cylinder seat, a cylinder mounted thereon, a piston movable in said cylinder, and an annular lubricating pad supported upon said flange adapted to be engaged by the piston upon the suction stroke of the latter, 85 the pad being exposed to the opening, whereby it will be moistened with the lubricant by the splash from the crank case.

4. In a tire pump of the character described, a crank case, a cylinder mounted 90 thereon, a piston operating in the cylinder, a shaft passing through the crank case, means operatively connecting the shaft to the piston to reciprocate the latter, a baffle flange formed at the junction of the crank 95 case and the cylinder, a lubricating pad supported upon the flange and adapted to be compressed by the piston upon its suction stroke, and means whereby lubricant may be disposed in the lower portion of the crank 100 case, there being an open space between the crank case and the adjoining portion of the cylinder and the pad being exposed to such space, as and for the purpose set forth.

5. In a pump, a crank case, a cylinder 105 detachably mounted upon the crank case, a shaft passing through the crank case, a piston having a depending member longitudinally slotted to embrace the shaft, the slot opening at the lower end of the member, whereby said depending member may be dropped into position over the shaft when the cylinder is removed, and an actuating 110 member mounted on the shaft and disposed at the side of said member and operatively 115 connected with the piston.

6. In a pump, the combination with a base having an oil chamber located therein, of a cylinder arranged above the base, a piston reciprocating within the cylinder, a baffle 120 located at the bottom of the cylinder, an absorbent member disposed above the baffle in juxtaposition thereto, and deflecting means on the lower face of the piston.

7. In a pump, the combination with a 125 crank case and cylinder, of a shaft passing through the crank case, a piston having a guiding member provided with an open ended slot for removably engaging said shaft and an actuating member mounted on 130

the shaft and pivotally connected with the piston.

8. In a pump, the combination with a cylinder and reciprocating piston, of a drive shaft, a pair of eccentrics mounted on the drive shaft in spaced relation to each other and pivotally connected with said piston, and a guiding member carried by said

piston, the guiding member being located between said eccentrics and having an open ended slot removably engaging the drive shaft.
